BERIAH M. THOMPSON, OF CHEYENNE, WYOMING

APPARATUS FOR CLEANING BOILERS

Application filed June 24, 1927. Serial No. 201,267.

(GRANTED UNDER THE ACT OF MARCH 3, 1883, AS AMENDED APRIL 30, 1928; 370 O. G. 757)

My invention relates broadly to apparatus for cleaning boilers of stationary or moving steam power plants and more particularly to cleaning boilers installed on ships.

The object of my invention is to provide an apparatus that will reduce the time consumed by the present methods of cleaning boilers. With the apparatus now in use it has been necessary to remove the side casings of the boilers, the soot cleaning doors and the baffles. The usual method is to manually clean away the soot and solid external deposit that has collected around the base of the tubes, to a thickness which may vary from two to six inches and more in thickness, by means of a brush or other instrument. This method is not only expensive but usually consumes several weeks for a complete cleaning of a boiler. But with my apparatus one man and one of my devices may clean such boiler in a day, or two men and said devices, one for each nest of tubes, may accomplish this work in half a day, far better than the same may be done manually.

Furthermore from the natural construction of the boiler it is practically impossible to reach every point around the tubes and clean the soot therefrom by any manual means.

Steam or compressed air, with or without sand, will not efficiently remove said combustion deposit; while such sand blast in the hands of other than the most skilled operator is quite likely to unduly wear, or cut through, the boiler tubes, especially where said deposit is of variable thickness, as it usually is, and the difficulty of distinguishing, under ordinary working conditions, when the deposit has been cut through at any place and when such sand is cutting into any tube.

In the apparatus that I have developed it is only necessary to allow the boiler to cool and to have the fire box cleaned out when the work of cleaning the boiler may be started.

Further objects of my invention will appear more fully hereinafter as the description of the apparatus is developed.

My invention consists substantially in the construction, combination and arrangement

of parts associated therewith as will be more fully hereinafter set forth, as shown by the accompanying drawings, and finally pointed out in the appended claims.

Reference is to be had to the accompanying drawings forming a part of this specification in which like reference characters indicate corresponding parts throughout the several views and in which:

Figure 1 is a view of the apparatus as applied to an inverted V-type boiler, which is shown partially in section, the right hand nest of tubes and drum 1 and wall 5 being broken away.

Figure 2 is a sectional view of a portion of the shield and the method of mounting the trough upon the boiler.

Figure 3 is a modification thereof,

Figure 4 is a sectional view of the packing strip,

Figure 5 is a view of my preferred form of clamping device,

Figure 6 is a view of the sprayer valve and nozzle, and

Figures 7, 8 and 9 are views of the tips of the different nozzles that I have used to wash the solid external combustion deposit out of the more inaccessible places around the base of the tubes.

Referring to Figure 1, numerals 1 and 2 represent lower and upper boiler drums respectively of an inverted V-type water tube boiler that are connected together by the usual tubes 3. The drums have been shown in section to more clearly show the method of the operation but it is to be understood that in actual practice it is not necessary to remove any of the boiler's parts to practice the said operation of cleaning since the entire apparatus is introduced within the fire chamber through the access door 4. A portion of the lower drum 1, next to the usual sloping top of the firebrick wall 5 is cleaned by scrubbing with steel wool or a wire brush until there is a clean surface along the drum between the tubes and the firebrick.

A large canvas shield is then hung from a point near the upper ends of the tubes 3 and secured at the lower end to the boiler along and upon the polished strip in a manner to

be hereinafter described, so that the usual parts of said boiler above said cleaned surface thereby become a part of said shield, said canvas shield being a removable supplement thereto.

Referring to Figure 2, numeral 6 represents a canvas trough that constitutes the lower portion of the canvas shield above referred to. The lower edge of the canvas shield is clamped within a packing member 7, shown in detail in Figure 4. This packing member is placed along the clean strip between the boiler and the firebox and is held rigidly in position by means of clamp 7a shown in detail in Figure 5.

At the lower portion of the canvas trough are a plurality of outlet tubes 8 that carry away the used water and waste material constituting the cleanings from the boiler. The tube or tubes 8 that are unattached to the run-off pipe or pipes, that pass through door 4, are plugged as shown at the left of Figure 1.

Referring particularly to Figure 3, I have shown a metal trough 9 to which the canvas shield is secured in any manner sufficient to insure a water tight connection between the trough and the shield. Upon this trough is mounted a packing strip similar to that to be described with reference to Figure 4. The mounting is practically identical with that of the trough shown in Figure 2.

Referring particularly to Figure 4, the packing member consists of a plurality of U strips 10 between which is clamped one edge of the metal or canvas trough 11 which is firmly held in position by means of bolts 12. Within the channel of the outer U member is a flexible packing strip 13 of rubber or like material. It will thus be seen that when any pressure is exerted against the boiler by the packing member a water tight connection is obtained.

It is to be understood that any clamping means that will secure a water tight connection between the packing strip and the boiler is sufficient. However, I have found that with the types of boilers upon which my inventions have been tried a flexible adaptable clamp of the form shown in Figure 5 is easily adaptable to the varying slopes between the tubes and the boiler drum, as well as adjustable to overcome the warping tendency of said tubes under high heat and internal pressure.

The clamp consists of two elements 15 and 16, having semicircular grooves near the outer end and adapted to fit varying sizes of tubes. Between the straight portions of the clamp there is initially pivotally mounted a threaded member 17 that carries a threaded screw 18 in its lower end. When the clamping elements are placed around the tubes said pendent members 17 may each be advantageously radially positioned about their piv-

otal connections to each of their respective clamping elements 15 and 16 to properly position their screws 18 to most efficiently engage the channels of U-member 10 whereby said screws 18 may, when tightened against member 10, position and retain the adjacent edge of shield 6. The several clamping units may then be rigidly clamped in position by means of bolts passed through the holes 19 and 20. The tip of the screw 18 is then placed in the channel of the U-member 10 shown in Figure 4, so that the flanges of member 10, between which screws 18 are extended, may secure in position the removable shield 6 even when some of the screws 18 inadvertently do not press against the web of said U-member 10; but in such contingency the rigidity of member 10, between the screws 18 that do bind against the web of member 10, will still exert sufficient tension upon the rubber strip 13 to form a water-tight union between it and said cleaned surface of drum 1 even at points where a screw 18 inadvertently should not be exerting tension against the web of member 10. It will thus be seen that the packing 13 may be pressed thus and thereby form a water-tight joint with and throughout the length of said cleaned surface of the wall of the boiler drum by advancing the screw 18 through the member 17 of each clamping unit.

The combustion deposit, formed upon all of the surfaces of the boiler exposed thereto, is far less conductive of heat than the metal forming said surfaces, so that said deposit must be frequently removed for efficient operation.

The water deposited scale formed upon the interior surfaces of such boiler tubes is of a wholly different nature and character than the combustion deposit formed upon the exterior surfaces of said tubes which my invention is specially adapted to remove rapidly and efficiently.

The constituents of said combustion deposits vary with the fuel used and with the conditions under which it is used.

A number of tests made of such deposits from different fuels disclose the following variations in constituents:

Ash content varying from about 40 per cent to about 70 per cent of the mass; volatile carbon content varying from about 30 per cent to about 62 per cent of the mass; and a content of water soluble constituents varying from about 3 per cent to about 20 per cent of the mass.

Other samples may vary further and include other substances.

I have discovered that the constituents of said deposits are finely divided and intimately commingled in the mass; that the said constituents that are water soluble are quickly liquified and washed out, of the interstices in said mass occupied by said water soluble con-

stituents, by the hot impacted liquid or water; that said evacuated interstices form channels for the entrance, and quick transmission of the effects, of said hot impacted liquid to a substantial depth of said mass and throughout the area of said mass so impacted; that one of the effects of said impacted liquid upon said mass is that the water-absorbent particles of said mass absorb said liquid; that said evacuated interstices increase the area and rate of said absorption; that said absorption expands the water-absorbent particles of said mass affected by said liquid; that said expansion sets up internal strains in said mass; that part of said mass is relatively brittle and non-elastic; that said internal strains may substantially fracture some samples of said mass in the area kept supplied with said liquid for a sufficiently long period; that when the area of said mass subjected to said internal strains is impacted externally its fracture is thereby facilitated; that said evacuated channels transmit the force of said impact through said fluid content of said channels and thus substantially augment said internal strains occasioned by said expansion; and that said mass is thereby quickly and readily fractured into relatively small particles, with little manual effort, and said particles fall to, and are washed from, the shield by the spent liquid.

In former boiler cleaning, when a blunt instrument was used to chip off said deposit, many blows were upon the parts of the boiler which tended to crystallize the metal thereof and shorten the life of the boiler; but with my invention substantially no vibrations are produced in the boiler and its parts and therefore no crystallization results, or is contributed to, from the use of my invention.

Liquid at atmospheric temperature will accomplish by impact the removal of said deposit in time, but by increasing said temperature substantially above atmospheric temperature its rate of removal of said deposit is substantially increased.

In the practice of my invention it has been found that water heated to a temperature of about 190 degrees and placed under a pressure of about 80 pounds per square inch gives satisfactory results when employed with my nozzles and shield and method so as not to wet the refractory linings which are in the form of firebrick work and indurated plastic work which are greatly deteriorated by moisture. Such work, when wet, requires long periods of application of a moderate continuous heat to dry it out before the same can be efficiently used; and if wet by the waste water, which may contain sulphurous and other acids, the drying out of said refractory linings leaves said acid effects. When said plastic work becomes wet it usually disintegrates, and when it or firebrick becomes wet and are

subjected to substantial heat the same are disrupted and fractured.

The lower drum 1, by my invention forms a part of shield 6. End pieces are also provided for shield 6 at points beyond the nest of tubes 3.

Pipe 21 conveys the impact water through the access door 4 and to the nozzle, which is insertable from, and along the upper edge of, said shield 6 so that the water discharged from said nozzle is projected with substantial force at a downward angle upon and along each of the tubes 3 and the combustion deposit thereon and there-between, disintegrating said deposit, until said water finally impacts upon and cleans the surface of drum 1.

Where said deposit fills the horizontal space between the tubes 3, the nozzle may be manually pressed at a downward angle against the adjacent face of said deposit, whereby the above described actions and reaction of absorption, washing out, expansion and fracture of the mass by the impact of the water in the direction of the longitudinal axis of said nozzle, said nozzle will be quickly imbedded, to the extent of its length, into said deposit with relatively slight manual pressure. Thereupon, the nozzle may be withdrawn and other holes successively likewise formed until the face of said deposit is honey-combed with such holes, which are formed therein a distance apart dependent upon the apparent character of said deposit. While other holes are being thus formed the water in said former formed holes is being absorbed into the surrounding area of said deposit causing expansion of the water-absorbent constituents thereof.

A nozzle, preferably with lateral openings, either 25, 26 or 27, is inserted into such formerly formed holes, whereby the laterally impacted hot water will complete the disruptive action of said expansion and wash out the fragments of said deposit progressively as said nozzle is moved manually toward the bottom of each of said holes. I have found that a nozzle with an opening only at its point will accomplish this work, but it requires a longer time, and the holes must be spaced closer together.

Some of the impacted hot water will be projected above the upper layer of tubes 3 when said nozzle breaks through the upper surface of said deposit; as well as when moistening, and then impacting water upon, the deposit upon said upper layer of tubes 3. Such water as is not absorbed by said deposit will drain down the upper surface of said deposit and form pools in the uneven areas of, or depressions in, said deposit, while the surplus water will drain laterally along the top of said deposit, in the region of the point of union between drum 1 and shield 6, Figure 1, and thence into shield 6 at the opposite ends of said deposit.

Said shield 30 is a usual part of said water-tube boilers and normally confines and directs the combusted and combusting products, coming through each nest of tubes 3, towards and to the stack. In such normal functions 5 said shield 30 has formed thereon said deposit, in a layer thining toward, and in spots near, its top, causing said shield 30 to become overheated in the areas occupied by said 10 deposit. Such overheating tends to weaken and buckle shield 30, as well as to ignite any oil that may drip, or dust that may collect, upon the external surface thereof, and to thus endanger the vessel or structure containing 15 such boiler. Said tendency is obviated by the removal from shield 30 of said deposit at frequent intervals, which removal my invention also most economically and efficiently accomplishes concurrently with the removal 20 of said deposit from each of the nests of tubes 3.

In my invention said shield 30 not only causes the hot impacted water from said nozzle, necessary to moisten, expand, fracture 25 and wash off said deposit therefrom, to be drained, with the sludge, onto the lower portions of the shield which I form of a part of water drum 1, and the supplemental temporary shield 6 which I attach thereto; but 30 said shield 30 serves the further function of catching and draining, ultimately into said shield 6, said water accidentally as well as necessarily projected above the upper layer of each nest of tubes 3 in the operation of cleaning 35 the same.

It is therefore apparent that said shield 6 functions as the flexible lower portion of, and is supplemental to, the much greater area of shield afforded in my invention by the 40 permanent shield 30, temporary shield 6 and the surface of said drum 1 between and adjoining the adjacent edges of said shields 6 and 30; and that my invention causes said shield 30 and said surface of drum 1 to serve 45 said additional function foreign to their normal uses, and in violation of the heretofore prevailing custom of keeping liquid from the combustion areas of boilers, which areas are usually lined with refractory material.

50 Thus, in my invention, inadvertent or accidental diversion of the liquid impacting nozzle occasions no injury, as said members 30, 1 and 6 function together as a shield of such ample proportions as to catch practically all 55 possible discharge of said nozzle. This enables a spare boiler to be cleaned while the vessel is at sea, or even during a storm, without wetting or injuring the refractory lining by such moisture or the placing of flexible 60 shield 6, which shield also prevents injury to the operator or operators who may be thrown off their balance by the motion of the vessel and against shield 6 and its edges.

65 For this purpose I supply the hot fresh water through a flexible pipe 21 that is led

through the access door and terminates in a sprayer 22. Attached to the sprayer is a nozzle 23 that may have the various tips shown in Figures 6 to 9 to direct the liquid into the more inaccessible places about the tubes.

The nozzle shown in Figure 6 is that of the diamond type 24 that is used for all direct work. The nozzle shown in Figure 7 has the diamond point 24 with a plurality of side slots 25 for directing the liquid from the sides of the nozzle. The nozzle shown in Figure 8 is similar to the one shown in Figure 6 except that one of the sides of the diamond point is sheared off on one side, as at 26, to direct the flow of liquid to one side. Also in the sides of the nozzle tube are a plurality of holes 27 that serve the same purpose as the side slots shown in Figure 7. The nozzle shown in Figure 9 is open ended and is used for direct washing of the larger surfaces between the boiler tubes.

Each of the nozzles is formed of tubing, the sides of which are flattened throughout the major portion of its length, as shown in Figure 6, in order to readily introduce the nozzle, to the extent of its flattened length, into the horizontal as well as vertical spaces between the tubes 3 of each tube nest, as well as to obtain a greater volume of liquid flowing at high velocity in a flattened stream than would be obtained from a round nozzle of a size readily introducible into said spaces. Said flat stream of liquid may be sprayed over a given surface quicker than by a round stream of the limited size, and its greater volume of discharge of impact liquid substantially lessens the time in which said deposit may be moistened, absorb, expand, disrupt and be washed away.

Said combustion deposit soon forms in constant use of the boiler and in thicknesses varying from two inches to six inches, especially over drums 1 and in the lower part of the tube nests, where, before my invention about ninety per cent of the failure of such tubes occurred.

The frequent use of my invention prolongs the efficient life of such boilers from one to two years longer than when my invention is not used.

The method that I have found most efficient is to allow the boilers to cool and have the fire removed from the fire box. As soon as the temperature of the fire box has lowered sufficiently to permit an operator to work therein the shield and trough are inserted through the access door. A strip is then cleaned along the sloping top of the firebrick wall 5, and below the tubes 3, and the shield 6 is mounted in the manner above described forming a water tight connection between the boiler and the packing member. The shield is then hung from the upper ends of the tubes.

After the shield and the trough have been secured in position the liquid or water conduit is led through the access door. The operator then works from above the shield and inserts the nozzle between the tubes and turns on the water. Beginning near the top of each pipe he follows the spaces between the boiler tubes 3 down to a point in close proximity to the lower boiler drum 1. By the use of this hot fresh water, I have found that the solid deposits that collect upon the tubes and more particularly that which solidified into a compact mass near the base of the tubes of the boiler is disintegrated to a sufficient fineness to be carried from around and between the tubes into the trough and through the outlet conduits.

I have tried many kinds of shields, but said flexible lower shield 6 has been most efficient, enables the operative or operatives to work efficiently and with safety in the close quarters where the same must be used, and especially when, to expedite the work, a separate shield 6 and one or more operatives are simultaneously employed for each nest of tubes 3, wherein such flexible shields 6 yield readily to, and are displaced by, the bodies of the operatives at points where the same is not then being used as a water and sludge shield. Said temporary displacements of said shields 6 afford ample working space for the operatives and the nozzles and their hose, and affords as safe gangway for the operatives substantially the whole area between the upwardly converging water tubes 3, and contact with said flexible shields 6 affords the operatives warning that harder substances are being approached.

An unflexible and unyielding shield 6 could not be employed without sacrificing the aforesaid advantages, and must be made in small sections, to get them into and out of the door 4, with liability of leakage in each joint between such sections, and require more time for assembling each shield 6, besides affording less room for the operatives, more liability of injuring them or the refractory lining by accidental contact therewith, and preclude more than one such rigid shield being used in the same combustion chamber at the same time.

By this method and apparatus it will be seen that by applying hot water under pressure in the manner above described that sections of a boiler may be thoroughly cleaned in an operation that consumes very little time in comparison with that necessary for cleaning the same boiler by the methods and apparatus heretofore used. This substantial saving of time that a boiler must be out of commission while being cleaned of combustion deposit is of material commercial value, and in war time said value is accentuated.

The facility with which my invention enables a spare boiler to be cleaned while its

vessel is in operation further enhances its advantages.

It will be understood that the above description and accompanying drawings comprehend only the general and preferred embodiment of my invention and that minor detail changes in the construction and arrangement of parts may be made within the scope of the appended claims without sacrificing any of the advantages of my invention.

In my co-pending application, Serial No. 201,268, I have claimed the method herein disclosed incident to the better understanding of the inventive concept of the herein disclosed and claimed apparatus for the efficient practice of such method.

The invention herein described may be manufactured and used by or for the Government of the United States for governmental purposes without the payment to me of any royalty thereon or therefor.

Having thus described my invention, what I claim is as follows:

1. In a boiler cleaning apparatus, the combination of a boiler having tubes subject to accumulation of combustion deposit, a metallic member, a flexible shield secured to said member and means for mounting the shield and said member below the tubes of a boiler, and means for passing within the boiler and applying to said deposit a fluid.

2. In a boiler cleaning apparatus, the combination of a boiler having tubes subject to accumulation of combustion deposit, a metallic member, a flexible shield secured to one side of said member, a packing element secured to the opposite side of said member, means for effecting a water tight seal between the packing element and the boiler, and means for removably securing the opposite side of said shield.

3. In a boiler cleaning apparatus, the combination of a boiler having tubes subject to accumulation of combustion deposit, a metallic member, a flexible shield secured to said member, a packing element secured to said member, said packing element including a U-shaped member engaging the side of the member, a packing strip on channeled surface of said U-shaped member, and means for effecting a watertight seal between the packing element and the boiler.

4. In a boiler cleaning apparatus, the combination of a boiler having tubes subject to accumulation of combustion deposit, a metallic member, a flexible shield secured to said member, a packing element secured to said member, said packing element consisting of a compressible water-proof strip secured to said member, means for effecting a watertight seal between said strip and the boiler, said means consisting of a plurality of clamps engaging the tubes of the boiler and having each a part adjustable against said packing element.

5. In a boiler cleaning apparatus, the combination of a boiler having tubes subject to accumulation of combustion deposit, means for applying liquid upon the combustion deposit, a flexible shield, means for removably mounting said shield below said deposit to be cleaned, and means whereby waste may be conducted from said shield.
- 10 6. In a boiler cleaning apparatus, the combination of a boiler having tubes subject to accumulation of combustion deposit, means for applying liquid upon the combustion deposit, a flexible shield, end portions for said shield, means for removably securing said shield to portions of said boiler whereby said shield is held at a plurality of angles relative to a horizontal plane, and means whereby waste may be conducted from the low part of said shield.
- 15 7. In a boiler cleaning apparatus, the combination of a boiler having tubes subject to accumulation of combustion deposit, means for applying liquid upon the combustion deposit, a flexible shield, means for securing one side of said shield in bodily contact with a surface of said boiler, means for supporting the remainder of said shield, and means whereby waste may be conducted from said shield.
- 20 8. In a boiler cleaning apparatus, the combination of a boiler having tubes subject to accumulation of combustion deposit, means for applying liquid upon the combustion deposit, a flexible shield, means for removably securing said shield in a liquid-tight joint to a surface of said boiler, means for supporting the remainder of said shield, and means whereby waste may be conducted from said shield.
- 25 9. In a cleaning apparatus for water-tube boilers, the combination of a boiler having tubes subject to accumulation of combustion deposit, a plurality of clamping means for attachment to tubes of said boiler, a shield, means supported by said clamping means for securing one side of said shield, and means for securing another side of said shield to said boiler.
- 30 10. In a cleaning apparatus for water-tube boilers, the combination of a boiler having tubes subject to accumulation of combustion deposit, a plurality of clamping means for attachment to tubes of said boiler, a shield, means supported by said clamping means for securing one side of said shield, means for securing another side of said shield under said boiler, a hose coupling secured to said shield, and a hose attachable to said coupling.
- 35 11. In a boiler cleaning apparatus, the combination of a boiler having tubes subject to accumulation of combustion deposit, a flexible shield, means for removably mounting said shield adjacent that part of said boiler to be cleaned, and means for conveying waste from said shield at a plurality of different points.
- 40 12. An apparatus for cleaning the combustion deposit from the metallic portions of boilers comprising a boiler having metallic portions liable to combustion deposits and another portion liable to be injured by contact with water, means for passing within the boiler and applying liquid to said deposit to be cleaned, and means whereby said liquid is confined in its application within and conveyed outside of said boiler without wetting other than said metallic portions to be cleaned.
- 45 13. An apparatus for cleaning the combustion deposit from the metallic portions of boilers comprising a boiler having metallic portions liable to combustion deposits and another portion liable to be injured by contact with water, means for passing within the boiler and applying liquid to said deposit to be cleaned, a shield, and means for so removably mounting said shield that portion of said boiler above said shield also functions to drain the spent liquid into said removable shield.
- 50 14. An apparatus for cleaning the combustion deposit from the metallic portions of boilers, including in combination a lower drum, tubes rising therefrom, a deflecting shield extending from said drum upward for normally directing the combustion products, a supplemental shield, means for applying liquid to said deposit to be cleaned, and means for so removably mounting said supplemental shield that it may catch the spent liquid drained from said deflecting shield, drum and tubes.
- 55 15. An apparatus for cleaning the combustion deposit from the metallic portions of boilers, including in combination a lower drum, tubes rising therefrom, a deflecting shield extending from said drum upward for normally directing the combustion products, a supplemental shield, means for applying liquid to said deposit to be cleaned, and means whereby said supplemental shield may be removably secured with one of its edges forming a liquid-tight joint with a surface of said drum below said tubes and said supplemental shield may catch the spent liquid drained from said deflecting shield, drum and tubes.
- 60 16. An apparatus for cleaning the combustion deposit from the metallic portions of boilers, including in combination, a lower drum, tubes rising therefrom, a metallic deflecting shield extending from said drum upward for normally directing the combustion products, means for applying liquid to said deposit to be cleaned, a flexible supplemental shield, a rigid member secured to one edge of said supplemental shield, and means whereby said supplemental shield may be removably mounted with its said member forming a liquid-tight joint with a surface of said drum below said tubes.

uid-tight joint with a surface of said drum below said tubes and said supplemental shield may catch the spent liquid drained from said deflecting shield, drum and tubes.

5 17. In apparatus for cleaning the combustion deposit from boilers, the combination with a boiler, having an access door leading to the parts of the boiler to be cleaned, and refractory material associated with said parts to be cleaned, of means passing through said door for applying a cleaning medium to the area to be cleaned, means for preventing said medium from contacting with said refractory material and means whereby the waste from the cleaning operation may be conveyed from said boiler.

10 18. In apparatus for cleaning the combustion deposit from boilers, the combination with a boiler, having an access door leading to the parts of the boiler to be cleaned, and refractory material associated with said parts to be cleaned, of means passing through said door for admitting a confined cleaning medium, manually operable valve controlled means communicating with said first named means within said boiler for applying said medium to the surfaces to be cleaned, means for preventing said applied medium from contacting with said refractory material, and means whereby the waste from the cleaning operation may be conveyed from said boiler.

15 19. In apparatus for cleaning the combustion deposit from boilers, the combination with a boiler, having a door leading to the parts of the boiler to be cleaned, and refractory material associated with said parts to be cleaned, of portable means passing through said door for delivering a confined cleaning medium, portable manually operable valve controlled means within the boiler introducable through said door and communicating with said delivery means for applying said medium to the boiler surfaces to be cleaned; and portable means removably secured within the boiler introducable through said door for receiving and conveying from said boiler, substantially without contact with said refractory material, the applied medium and waste from the cleaning operation.

20 20. In apparatus for cleaning the combustion deposit from boilers, the combination with a boiler, having a door leading to the parts of the boiler to be cleaned, and refractory material associated with said parts to be cleaned, of portable means for passing through said door for delivering a confined cleaning medium, portable manually operable means within the boiler introducable through said door and communicating with said delivery means for applying said medium to the boiler surfaces to be cleaned, manually operable means communicating with said delivery means within the boiler and

convenient to the hand of the operator adjacent the parts to be cleaned for controlling the rate and direction of application of said medium; and portable substantially flexible means removably secured within the boiler introducable through said door for receiving and conveying from said boiler, each substantially without injurious contact with refractory material, the applied medium and waste from the cleaning operation.

21. In a cleaner for boilers having tubes closely nested together and subject to accumulation of combustion deposit on and between the tubes, the combination with means for supplying a confined cleaning medium within the boiler, of a manually portable nozzle having a thin, long, flat spraying end and an integral short substantially round base portion of a diameter larger than the short diameter of said flattened nozzle, said flattened end being adapted to pass between said closely nested tubes whereby the spraying end of said nozzle may be introduced between the nested tubes in the cleaning operation, means for removably attaching said base portion of said nozzle to said supply means, and means for controlling the discharge of said nozzle.

22. The apparatus of claim 1 with said mounting means being characterized as adjustable.

23. The apparatus of claim 1 with said mounting means being characterized as including a plurality of adjustable portions each having a screw adapted to secure said member in place.

24. The apparatus of claim 1 with said mounting means characterized as including a plurality of clamps adapted to be removably secured to said tubes, means adjustably secured to said clamps, and a screw mounted in said adjustable means and adapted to secure said member in place.

BERIAH M. THOMPSON.
